UNITED STATES PATENT OFFICE

135,710

DESIGN FOR A JACKET

Helen C. Cookman, New York, N. Y.

Application March 9, 1943, Serial No. 109,703

Term of patent 7 years

To all whom it may concern:

Be it known that I, Helen C. Cookman, a citizen of the United States, residing at New York, county of New York, and State of New York, have invented a new, original, and ornamental Design for a Jacket, of which the following is a specification, reference being had to the accompanying drawing, forming part thereof.

Fig. 2 is a back view of the jacket.

I claim:

The ornamental design for a jacket, as shown.

HELEN C. COOKMAN.
